UNITED STATES PATENT OFFICE.

ALFRED RISHWORTH TATTERSALL, OF LONDON, ENGLAND.

APPARATUS FOR MAKING FLOUR AND MEAL.

1,037,805.

Specification of Letters Patent.

Patented Sept. 3, 1912.

Application filed September 25, 1909. Serial No. 519,594.

To all whom it may concern:

Be it known that I, ALFRED RISHWORTH TATTERSALL, a subject of the King of Great Britain, residing at 75 Mark Lane, in the city and county of London, England, have invented new and useful Improvements in Apparatus for Making Flour and Meal, of which the following is a specification.

This invention relates to improvements in self-contained machines for making flour, corresponds to Letters Patent of Great Britain No. 23,836 of 1909 granted to me therefor, and is an improvement upon the machine disclosed in Letters Patent of Great Britain granted to me the second day of June, 1904, No. 12,492.

The present invention has for its object to provide a complete flour mill, all the constituent elements of which are contained in a single frame, which is so organized as to produce flour, clear and free from impurities, and which shall retain as much as possible the sweet flavor of the wheat berry and the qualities known in the art as strength and liveliness.

So far as I am aware, the first instance of a complete flour mill organized with the constituent elements contained in a single frame is that disclosed by my hereinbefore mentioned Letters Patent of Great Britain, No. 12,492 of June 4, 1904. The mill organized as disclosed in that patent, however, presents certain difficulties and imperfections which are avoided in the mill organized according to this present invention, as will appear hereinafter.

As shown in the accompanying drawings, the machine of my invention is organized with two pairs of break rolls, two pairs of reduction rolls, four centrifugals, and appropriate conveyers, to constitute a complete automatic self-contained roller milling plant capable of turning out about 140 pounds of flour per hour.

In said drawings,—Figures 1 and 1^a are longitudinal sections through my improved apparatus. Fig. 2 is a cross section through the roller portion of the apparatus. Fig. 3 is a cross section through the scalping and dressing portion of the apparatus.

In the said drawings, the reference numerals 90 and 91 designate a two-chamber casing supported by a suitable frame. These casings are designed to be dust tight and in one, 90, of said chambers the sets of break rolls and reduction rolls are con-

tained. The centrifugals are disposed in the other chamber of the casing, and suitable conveyers as hereinafter set forth serve to conduct the product of the break rolls and reduction rolls into the centrifugals. In the casing chamber 90 is arranged a feed roll 1, below which are arranged a pair of break rolls 5 and 6, the latter being adjustably mounted. Immediately below the first pair of break rolls 5 and 6 I arrange a scalper sieve 7 onto which the product of said rolls falls. That which does not pass through the mesh of the sieve drops by gravity onto an inclined slide 16 which guides the same to the second pair of break rolls 27, 28, arranged beneath the first set of rolls. That portion of the product of the first set of rolls which passes through the sieve 7 is taken immediately by the conveyer 8 into the centrifugal dresser 9 and the flour resulting from the operation of the first break rolls passes through the silk covering of this centrifugal as a finished product, and, being guided by the slides 29 and 39, goes to the conveyer 30 at the bottom of the machine casing. The tailings from this centrifugal require to be further reduced and dressed before the bran is separated therefrom as a finished product. For the purpose of convenience of description, the coarse of the tailings of this first centrifugal 9 will be left until the tailings from the sieve scalper 7 have been brought to substantially the same state.

It will be observed that, so far as yet described, the present invention differs from the machine shown in my hereinbefore-referred-to British Letters Patent No. 12,492 in this: that is to say, according to the present invention the product of the first pair of break rolls falls immediately onto a vibratory scalper sieve, and the tailings go thence immediately to the second pair of break rolls, the "throughs" only being conveyed to the first centrifugal dresser; whereas, according to the said British Letters Patent, all of the product of the first break-rolls is taken by a conveyer and transported into a rotary scalper arranged interiorly of a centrifugal dresser. This distinction is a very important one for the following among other reasons: According to the mode of operation which is carried out by the mechanism organized as disclosed in the said British Letters Patent the result, in practice, was found to be that the severe action

of the rotary-scalper arranged interiorly of the centrifugal-dresser in sifting the ground stock through the mesh of the scalper, immediately followed by a correspondingly severe beating in the centrifugal dresser, tended to break up the dust and bran particles coming from the first break rolls and to a considerable extent color the flour sifting through this centrifugal dresser to an objectionable blue tint. On the other hand, I have discovered that by providing a vibratory scalper-sieve arranged below the first pair of break-rolls, and onto which the product of those rollers falls, this objection is avoided. And I attribute this result, in part, to the more moderate and gentler action of the scalper-sieve as compared with that of the rotary scalper arranged interiorly of the centrifugal dresser. I attribute the result, also, in part, to the fact that according to the organization shown in the before mentioned British Letters Patent the entire product of the first break-rolls, is, before separation, conveyed, in a mingled state, to the combined rotary-scalper and centrifugal-dresser of the British Letters Patent, with opportunity for the breaking up, by attrition, of the dust and bran particles coming from the first break rolls, an occurrence which is avoided by the arrangement of a vibratory scalper-sieve immediately below the first break rolls according to the present invention, by which separation of the product of said rolls is immediately effected and only the "throughs" of the sieve are conveyed to the centrifugal dresser. Another advantage of this difference in organization is that the maximum flavor of the wheat berry in the flour and the natural liveliness of the flour in the dough is preserved by a reduction in the amount of handling of the flour stock. It is known that the oxidation of the flour oil deprives the flour of flavor as well as strength. The more handling the flour undergoes the more the oil is oxidized, and, consequently, the less flavor it has, and the less livelier it is in working up into dough. According to the organization of the British Letters Patent the entire product of the first break-rolls is conveyed to the rotary scalper arranged interiorly of the first centrifugal dresser and the tailings from that scalper have to be carried again out of the scalper to the second pair of break-rolls. This objectionable handling of the flour, with its resulting detractions from the flavor and liveliness of the flour, is avoided by my present invention, according to which the tailings from the vibratory scalper sieve fall and are immediately guided to the second pair of break-rolls.

Another important object of the invention is to separate the bran as a finished product, as quickly as possible, to avoid the proba-

bility of bran dust or bran particles passing off with the flour and imparting an undesirable dark color to the latter as a mass. Therefore, the tailings from the sieve scalper 7, after having been delivered directly to the second pair of break rolls 27, 28, and subjected to the action thereof, are taken immediately by the conveyer 36 into the centrifugal dresser 25 where the flour dresses through as a finished product and goes to the conveyer 30 before mentioned. The product which is thus conveyed to this centrifugal dresser 25 has undergone the action of two pairs of break rolls and comprises part flour, part bran, and part material which has to be further reduced. As before stated, it is desirable to deliver this finished product, bran, as quickly as possible. I, therefore, at the finishing end of this centrifugal provide a cut-off 16 which, as shown, consists of a covering for the dresser frame of coarser mesh than that through which the flour is dressed. This cut-off is surrounded by a casing 69 which, as shown in Fig. 3, is in communication with the conveyer 32. The bran in the centrifugal 25 does not pass through the material of this cut-off, but passes from the dresser as a finished product and is spouted to any suitable place of deposit. One of the chief objects of the novel arrangement of my invention—that is to say, the separation of the bran at an early stage of the process, avoiding the contamination of the flour, which exists in mills where the bran is further carried along with the flour and middlings—has thus been obtained.

At this point it is well to refer to the second distinct departure from what is disclosed in my British patent of 1904 before referred to. In that patent the product of the second break rolls passes into a double centrifugal, having an interiorly arranged rotary scalper by which the bran is separated out; whereas according to the present invention in this second centrifugal the first action is to sift out the finished product, flour, and at the tail or finishing end there is a scalper which operates to separate the middlings from the bran. The former go to the first reduction rolls and the latter is spouted off as a finished product. The material which passes through the cut-off or scalper 16 is delivered immediately to the conveyer 32 and for this purpose the dresser is provided with a brush 51 which sweeps the material out of the casing 69 into the conveyer. The difference in construction, arrangement and mode of operation just described is very materially important in respect of the character of the flour product, for, again comparing the arrangement with that of my aforesaid British Letters Patent of 1904, it will be observed that in the British patent the products of the second break-rolls are subjected to the severe action of the rotary

scalper arranged interiorly of the second centrifugal dresser, and, immediately, the "throughs" of this rotary scalper are subjected to another severe beating in the centrifugal dresser, which mode of operation presents just the same difficulties as have hereinbefore been referred to in respect of the action in the first combined rotary scalper and centrifugal dresser of the British 5 patent. That is to say, the bran and dust particles are broken up by attrition and contaminate the flour. In contra-distinction, according to the present arrangement, the products of the second break-rolls pass into 10 the centrifugal dresser without being first subjected to the severe action of the rotary scalper, and the flour sifts through this dresser with the least chance for contamination by the bran particles, and at the 15 finishing end of this dresser there is the scalper or cut off which separates the bran, as a finished product, and the middlings, which are to go to the first reduction rolls. The material which passes through the cut- 20 off or scalper at the finishing end of the second centrifugal dresser is now substantially like, and in substantially the same condition, as the tailings from the dresser 9 which had passed through the sieve 7, and constitutes 25 the tailings of the first centrifugal 9, and is in condition for further reduction. Therefore, I have provided a chute 31, see Fig. 3, which conveys the tailings from the centrifugal 9 into the conveyer 32 to which the 30 material that has passed through the cut-off 35 16 is delivered, and the conveyer delivers the middlings to the first pair of reduction rolls 40, 41. When acted upon by these reduction rolls, the product contains a sufficient 40 amount of free offal to make it desirable to deliver the latter as a finished product. It is taken by the conveyer 42 and delivered into the centrifugal 45 which is similar to 25, having a like cut-off 16 inclosed by a 45 similar casing 69. The flour is dressed through this centrifugal and goes as a finished product to the conveyer 30. The offal, which does not pass through the cut-off fabric, is delivered from the centrifugal 50 and spouted off to a suitable place of deposit. The middlings, which pass through the cut-off are taken by means of the conveyer 34 and delivered to an elevator 46 which discharges the material into the sec- 55 ond pair of reduction rolls, which, according to the organization of machine shown, are the final reduction rolls. The material after having been reduced by these rolls is passed through a final dresser 54, the flour 60 being dressed out and the residue delivered as a finished offal product.

Aside from the advantages in the mode of operation, and the improvement in the product resulting therefrom, which characterizes the arrangement of the first break-

rolls, vibratory scalper sieve, first dresser, second pair of break-rolls, and second centrifugal dresser with a scalper or cut-off at its finishing end, which have been hereinbefore described, the arrangement is otherwise materially improved in actual practice. One instance of such practical advantage is that serious mechanical troubles developed in the practical use of the machine of said British Letters Patent: (a) there was repeated breakage of the beaters in the interiorly arranged rotary scalper; (b) whenever the machine exceeded its normal speed these beaters expanded and fouled the cylinder; (c) there was in that arrangement no possible means of readily cleaning the wire covering of said interiorly arranged rotary scalper—that got choked up and did not dress out well. All these several objections are entirely avoided by the arrangement of the vibratory scalper in an accessible place immediately below the first break-rolls, and the elimination of the objectionably acting and practically inaccessible rotary scalper of the British patent, which the miller 90 could not readily get at to deal with.

The several operative parts may be mounted and driven as shown in the drawing. The feed roll 1 is shown as driven by means of a belt and the pulleys 2 and 3 from the 95 shaft 4 of the fixed first break roll 5. The centrifugal dresser 9 is supported at one end in a bearing 10 and at the other end on the worm shaft 11. This worm shaft is driven by a spur wheel 12 from the spur 100 wheel 13 secured to the roll shaft 4, and to the shaft 11 are secured the feeders of the centrifugal dresser 9. The ends of the centrifugal dresser 9 consists of a casing 140 and 141, the frame thereof being formed of 105 metal bars covered with silk or wire in the usual way. This centrifugal 9 is driven by means of the spur wheel 33 and the idle pinion 23 from the spur wheel 24, which latter is secured to the centrifugal 25. The 110 conveyer 36 is driven by spur wheels 37 and 38 from the shaft 57, which is the main driving shaft of the machine.

The ends of the centrifugal 25 consist of castings 20, 21, the frame thereof being 115 formed with metal bars covered with silk or wire in the usual way. The casting 21 is provided with a bearing 18 to support the shaft 36.

The two pairs of reduction rolls are fitted 120 with automatic feeds consisting of two inclined boards, one of which 70 is fixed, and the other, 71, hinged at 72, the bottom edges of the boards being maintained in contact by means of a spring 73 until sufficient 125 weight of stock has accumulated between the boards to overcome the pressure of the spring and allow the stock to fall in a thin sheet uniformly along the rolls.

The fixed reduction rolls are provided 130

with scrapers 55, it having been found in practice that one scraper is sufficient to keep both the fixed and the adjustable roll free from ground stock.

5 The apparatus is driven from any convenient source of power by means of a belt passing over the pulley 56 on the shaft 57. On the shaft 57 is a pulley 92 wide enough to take three belts 58, 59 and 60, of which 10 the belt 58 drives the first break rolls, the belt 59 drives the first reduction rolls, and the belt 60 drives the second reduction rolls.

The vibrating boards 29 and 39 below the two upper centrifugals are boards hung 15 on hinges 68, which boards are lifted and lowered once per revolution of the centrifugal cylinders by means of cams 69 secured to the inlet or outlet ends of the same.

By this invention a complete automatic 20 flour mill is contained in one machine and the material being made into flour or meal is not touched by hand from the time it falls into the feeding hopper till it is sacked off as flour, bran and offal.

25 For convenience of transport the apparatus may be made in such a manner that the frames are as light as possible and are connected by braces or tie bars when the machine is erected; for the same reason the 30 shafts connecting the rolls to the dressing portion of the apparatus may be made in two pieces which engage with each other by means of square projections 68, on the roller portion of the shafts, which engage with 35 similarly shaped recesses in the dressing portion of the worm shafts, these shafts being supported in bearings 63 secured to the worm casing by the bracket 64. Or the two portions of the worm shafts may be connected together by means of sleeve couplings 40 made in halves bolted together, the shafts being provided with sunk keys which engage with key-ways in the couplings. The worm is continued on the outside of the 45 couplings.

The portions 61 of the worm troughs 50, which convey the stock to the centrifugals, are fixed to the frame which supports the rollers, while the portion 66 of the worm 50 troughs are formed integral with the heads of the centrifugals and rotate therewith.

65 is a collar to prevent escape of dust.

67 is a fan to remove dust from the machine and to keep all cool.

Having thus described the invention what 55 is claimed is,—

1. In a self-contained flour mill, the combination of a casing, a plurality of pairs of break-rolls, a plurality of reduction rolls in the casing below the break-rolls, a scalping 60 sieve below the first pair of break-rolls, means for guiding tailings from said scalper to the second pair of break-rolls, a centrifugal dresser, means for delivering the material passing through the scalper sieve there- 65 to, a second centrifugal dresser for the stock from the second pair of break-rolls, pro- vided at its finishing end with a scalper, and means for delivering the product of the second pair of break-rolls to said second 70 centrifugal dresser.

2. In a self-contained flour mill, the combination of a casing, a plurality of pairs of break-rolls, a plurality of reduction rolls in the casing below the break-rolls, a scalping 75 sieve below the first pair of break-rolls, means for guiding tailings from said scalper to the second pair of break-rolls, a centrifugal dresser, means for delivering the material passing through the scalper sieve there- 80 to, a second centrifugal dresser for the stock from the second pair of break-rolls, pro- vided at its finishing end with a scalper, means for delivering the product of the sec- 85 ond pair of break rolls to said second cen- trifugal dresser, means for delivering the tailings of the first centrifugal dresser and the material passing through the scalper at the finishing end of the second centrifugal dresser to the first pair of reduction rolls, 90 another centrifugal dresser provided with a cut-off, for dressing the product of the first reduction rolls, means for delivering the stock passing through the cut-off portion of said last-mentioned centrifugal dresser to 95 the second reduction rolls, and a centrifugal dresser for the product of second reduction rolls.

ALFRED RISHWORTH TATTERSALL.
